UNITED STATES PATENT OFFICE.

JOHANNES VOPEL, OF BERLIN-NEUKOLLN, GERMANY, ASSIGNOR TO C. LORENZ AKTIENGESELLSCHAFT, OF BERLIN-TEMPELHOF, GERMANY.

CARRIER-FREQUENCY TELEGRAPH SYSTEM.

Application filed January 5, 1926, Serial No. 79,298, and in Germany January 20, 1925.

In carrier frequency telegraph systems the self-inductance of the lines presents special disadvantages in so far as the transmitted signals thereby undergo a retardation, these disturbances being specially remarkable with pupinized lines. A sign transmitted by means of an undamped alternating current requires a considerable time in order to build up. In consequence a relay interposed will not be actuated at once at the beginning of the sign, but only after some time. It is the object of the present invention to overcome this inconvenience, by interconnecting a resonant circuit tuned to the frequency employed and which produces an increase of the starting amplitude of the individual signs at the sending station and henceforth an increase of the steepness of the incoming wave at the receiving station.

The invention will be best understood by reference to the accompanying drawings of which Figure 1 shows an ordinary telegraphic sign, Figure 2 its corresponding shape at the receiving station, Figure 3 the hook-up according to the invention, Figures 4 and 5 the shape of the signs as modified according to the invention, whereas Figure 6 shows an application of the invention in connection with a double-acting key. In Figure 3, 1 means an alternating current generator, 2 and 3 are coupling coils, 4 is a self-inductance, 5 a capacity, 6 a keying device, 7 a transformer and 8 and 9 represent the transmission line. If the circuit consisting of the self-inductances 3 and 4 and capacity 5 is tuned to the frequency generated by the generator 1, it acts like a fly-wheel circuit into the transmission line. However by value of the loading by the key the amplitude will soon decay to the value determined by the steady current supply. A sign produced in this way at the transmitting station is shown by Figure 4. At the receiving station the sign will then look somewhat as indicated by Figure 5 and it may be seen that the steepness of the received wave due to the increased starting energy has been increased. The amplitude in contrast to the case represented by Figure 2 is building up quickly. A relay interconnected is responsive at an earlier time than in the case according to Figure 2. At the end of the signs after opening the key the oscillatory circuit builds up once more, thus presenting at the beginning of the following sign new reinforced energy. The

limit value the amplitude endeavors to attain after a longer time, will in both cases be the same depending only on the energy supplied by the alternating current source.

The invention may also be employed in connection with a double-acting key as represented by way of example by the diagram of connections in Figure 6. The alternating current source 1 is working over the coupling coils 2 and 3 upon two resonant circuits (4^a, 5^a) and (4^b, 5^b). These two circuits are controlled by a double-acting key (6^a, 6^b) which connects alternately the one or the other circuit with the transformer 7 and thereby with the line 8 and 9. By keying these two circuits currents are transmitted into the line which are displaced by 180° with respect to each other and which produce when being commutated at the receiving station alternately a positive and a negative current operating a suitable receiving apparatus.

What I claim is:

1. In a carrier frequency transmission system, in combination an alternating current source, a repeating transformer having its primary connected with said current source, a pair of circuits resonant to the carrier frequency and containing each one half of the secondary of said repeating transformer and a capacity, a double acting key in connection with the arrangement to connect alternately the one or the other of said pair of resonant circuits with a transmission line.

2. In a carrier frequency transmission system, in combination an alternating current source, a repeating transformer having its primary connected with said current source, a pair of circuits resonant to the carrier frequency and containing each one half of the secondary of said repeating transformer an inductance coil and a capacity, a double-acting key in connection with the arrangement to connect alternately the one or the other of said pair of resonant circuits with a transmission line.

3. In a carrier frequency transmission system, in combination an alternating current source, a repeating transformer having its primary connected with said current source a pair of circuits resonant to the carrier frequency and containing each one half of the secondary of said repeating transformer and a capacity, a second repeating transformer having its primary by means of a double-

acting key alternately connected with one of said resonant circuits and having its secondary connected with a transmission line.
4. In a carrier frequency transmission system, in combination an alternating current source, a repeating transformer having its primary connected with said current source a pair of circuits resonant to the carrier frequency and containing each one half of the secondary of said repeating transformer an

inductance coil and a capacity, a second repeating transformer having its primary by means of a double-acting key alternately connected with one of said resonant circuits and having its secondary connected with a transmission line.¹⁵

In testimony whereof I have affixed my signature.

JOHANNES VOPEL.
